US00D617622S

(12) **United States Design Patent**
Lopano

(10) **Patent No.:** **US D617,622 S**
(45) **Date of Patent:** **** Jun. 15, 2010**

(54) **IMPACT DRIVER**(75) Inventor: **Daniel N. Lopano**, Bel Air, MD (US)(73) Assignee: **Black & Decker Inc.**, Newark, DE (US)(**) Term: **14 Years**(21) Appl. No.: **29/344,544**(22) Filed: **Sep. 30, 2009**(51) LOC (9) Cl. .... **08-04**(52) U.S. Cl. .... **D8/68**(58) **Field of Classification Search** .... **D8/14.1, D8/61, 62, 63, 64, 65, 66, 67, 68, 69, 70; 81/57.11, 429, 454, 455, 456, 469, 489; 173/13, 104, 114, 168, 169, 170, 171, 178, 173/201, 211, 213, 217; 408/20, 124, 125, 408/234, 241 R; 451/358; 310/50; 227/8, 227/113, 114, 120, 130, 136, 142**

See application file for complete search history.

CLAIM

The ornamental design for an impact driver, as shown and described.

DESCRIPTION

FIG. 1 is a perspective view of the impact driver.

FIG. 2 is a front view thereof.

FIG. 3 is a rear view thereof.

FIG. 4 is a right view thereof.

FIG. 5 is a left view thereof.

FIG. 6 is a top view thereof; and,

FIG. 7 is a bottom view thereof.
